(57) **CLAIM**

We claim the ornamental design for a LED strip light, as shown and described.

DESCRIPTION

FIG. 1 is a perspective view of the LED strip light.

FIG. 2 is a front view of the LED strip light.

FIG. 3 is a back view of the LED strip light.

FIG. 4 is a side view of the LED strip light.

FIG. 5 is a side view of the LED strip light.

FIG. 6 is an end view of the LED strip light; and,

FIG. 7 is an end view of the LED strip light.

The LED strip light is shown with a symbolic break in its length. The appearance of any portion of the article between the break lines forms no part of the claimed design. The article is not limited to the scale shown herein.
